UNITED STATES PATENT OFFICE.

FREDERIC BILLON AND JACQUES BOHLI, OF SOLOTHURN, SWITZERLAND, ASSIGNEES
TO FIRM "SCINTILLA", OF SOLOTHURN, SWITZERLAND.

HORSESHOE-MAGNET.

1,401,130.

Specification of Letters Patent. Patented Dec. 27, 1921.

Application filed August 22, 1919. Serial No. 319,147.

To all whom it may concern:

Be it known that we, FREDERIC BILLON, a citizen of the Swiss Republic, residing at Solothurn, Switzerland, and JACQUES BOHLI,

5 a citizen of the Swiss Republic, residing at Oback, Solothurn, Switzerland, have invented certain new and useful Improvements in Horseshoe-Magnets, (for which I have filed an application in Switzerland, 10 August 29, 1918; Germany, Sept. 3, 1918, and Austria, July 1, 1919,) of which the following is a specification.

This invention has for its object to provide an improved horseshoe magnet of the 15 class of horseshoe magnets having a substantially cylindrical peripheral surface more particularly designed for magneto-electric ignition machines. A magnet of this class is made of a cylindrical piece of 20 steel which is cut with a parallel-sided slot that contains the shaft, and beginning at one end, stops short of the other end of the said piece. For the purpose of enabling this slot to be cut more readily with a milling 25 cutter, and for the purpose also of lengthening the path of the lines of force in the steel of the magnet which is desirable more particularly in the case of short magnets, an improved magnet according to this invention is formed at the end of the slot nearest 30 its yoke, with a hole having a diameter greater than the width of the slot. The axis of this hole is parallel to the sides of the slot and at right angles to the axis of 35 the magnet.

If the power of the magnet is determined on the one hand by its length and on the other hand by its cross-section, a definite ratio is found between the length and cross-section which is the most favorable for making the best use of the material as regards its magnetic properties. The form in which the magnet is used of course plays an important part as regards the magnetic 45 distribution conditions. But it is possible to determine for each case the most favorable ratio of length and cross-section for a magnet. Where a definite space is provided for the magnet it is possible that, for 50 instance, the horseshoe shape allows of making the best use of the material for the mag-

net. This is more especially the case when the space available has a relatively large cross-section and small length.

The present invention makes it possible 55 in this case that a given space is available for giving the horse-shoe magnet such form that the ratio of cross-section to length is the most favorable although for the length when employing the usual shape of horse- 60 shoe magnet the space is too small.

In the accompanying drawings which illustrate diagrammatically a constructional example of the improved magnet,

Figure 1 shows a front elevation thereof 65 and

Fig. 2 a cross sectional plan on the line $x-y$ of Fig. 1.

The improved magnet N. J. S. consists of a cylindrical piece of steel bent into the 70 form as shown with a parallel opening a between the leg members. A circular bore b is provided concentric with the outer contour of the magnet where it is bent into a semi-circular form as shown at J. It will 75 be seen from the diagram, in which a dotted line at the apex of the parallel members of the magnet shows the magnet before the circular bore b is formed that the cross section on line $x-y$ is not the same at the 80 yoke J as in the leg members.

Upon further reference to the drawings the curved lines c , d represent the lines of force, the normal path of line of force in the usual form is represented partly by a 85 full line and partly by a dotted line, the direction of the lines of force being indicated by the arrow heads; the line is practically central with the magnet structure.

In the present invention the line of force 90 is shown by the full line in which the curved part thereof follows a central path between the outer and inner faces of the magnet and owing to the section of the magnet at the yoke thereof being less than in the leg 95 portion the path of the lines of force as indicated by the line c embraces a greater length so that by this construction a greater effect is thereby obtained in the magnetic effect.

What we claim is:—

A horse-shoe magnet constructed of

a cylindrical steel bar bent to form a U-shaped cylindrical body, a parallel-sided slot symmetrically bifurcating said body from one end and terminating in a hole in
5 the yoke of said body parallel to said slot and perpendicular to said axis, said hole being of greater width than said slot in a

direction perpendicular both to said axis and said slot sides.

In testimony whereof we have signed our names to this specification.

FREDERIC BILLON.
JAK. BOHLI.
